UNITED STATES PATENT OFFICE.

GEORGE GOULD GOING, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPEWRITER.

1,403,494.

Specification of Letters Patent. Patented Jan. 17, 1922.

Application filed March 1, 1919. Serial No. 279,955.

To all whom it may concern:

Be it known that I, GEORGE GOULD GOING, a citizen of the United States, residing at Middletown, in the county of Middlesex and 5 State of Connecticut, have invented certain new and useful Improvements in Type-writers, of which the following is a full, clear, and exact description, such as will enable other skilled in the art to which it applies 10 pertains to make and use the same.

This invention relates to typewriting machines, and more particularly to instrumentalities thereof co-operable with a multi-color inking ribbon to permit printing in either 15 one of a plurality of colors.

It is one of the objects of the invention to provide an improved and reliable mechanism of the character mentioned adapted for application to a typewriting machine having 20 three printing case positions.

Further objects are to provide an improved ribbon guide operable at will to reverse an inking ribbon adjacent the printing point whereby the ink impregnated in the 25 ribbon may be impressed on the paper from either side of the ribbon, to utilize the latter to its full capacity, and to associate such a guide with the shiftable part of a typewriting machine having three case positions 30 whereby a multi-color ribbon may be efficiently used.

It is a further object to provide an improved mechanism of the character mentioned comprising parts capable of cheap 35 manufacture and assembly and possessing features of structural superiority and functional advantage.

Other objects and advantages will be in part noted hereinafter in connection with the 40 following description of the accompanying drawings, which illustrate a preferred, but exemplary, embodiment of the invention and in which—

Figure 1 is a rear elevation of the improved ribbon guide;

Fig. 2 is an end view thereof, taken from the left of Fig. 1;

Fig. 3 is a view similar to Fig. 1, but showing the parts in an adjusted position;

Fig. 4 is an end view of Fig. 3;

Fig. 5 is a schematic top view of the ribbon guide associated with the ribbon and ribbon spools;

Fig. 6 is a fragmentary perspective view 55 of the ribbon guide as mounted;

Fig. 7 is a rear view of a supporting and actuating part;

Fig. 8 is a top view thereof;

Fig. 9 is an end view of the same as mounted on a shift rail; and

Fig. 10 is a detail perspective of one of the parts shown in Fig. 5.

The mechanism illustrated is designed for mounting below and closely in front of a typewriter platen on which the writing paper is rolled, and includes a pair of spaced bent wire ribbon guides 1 and 2 rotatably mounted in bearings 3 arranged at the upper ends of arms 4 integral with a stamped metal main piece or bracket 5. A ribbon is adapted 60 to be threaded from one spool 6 around a yieldable pin 7, through the guide wires 2 and 1, around a second yieldable pin 9, to the other spool 10 (Fig. 5). It will be understood that the ribbon feed is reversible and 65 that the spools 6 and 10 serve alternately as takeup and delivery rolls.

The intermediate ribbon portion 11, which is held taut in registry with the printing point before the platen, is adapted for reversibility by rotation of the guides 1 and 2 70 in their bearings 3, and for this purpose said guides are provided with rigidly attached crank arms 12 beyond bearings 3 and to the ends of which are pivotally connected links 75 13 extending downwardly adjacent arms 4 and pivotally connected at their lower ends with bell cranks 14, in turn fixed to the extremities of a rock shaft 15 extending between and journaled in the arms 4. Said 80 rock shaft is provided at one end with a hub having thereon a pinion 16 which meshes with a toothed rack 17 at the end of an elongated lever 18 medially pivoted at 19 on an offset upstanding lug of the stamping 5. 85 The lever 18, on its rear face (that is, extending toward stamping 5), is also provided with two studs 20 and 21 equi-distant from the axis 19 and alternatively adapted for engagement by an actuating mechanism to be 90 described, whereby lever 18 may be rocked to swing rack 17 and thereby turn pinion 16 and shaft 15 to move connecting links 13 and 95 rotate guides 1 and 2 from the position shown in Fig. 1 through 180 degrees to the reversed 100 position shown in Fig. 3.

The actuating mechanism above mentioned includes a reciprocal plate 22 having a slot and pin connection 23, with the fore face of stamping 5 and carrying two 105 110

reversely disposed elements in the form of bell cranks respectively pivoted at the front and rear of spaced lugs 24 and 25 of sliding plate 22. The elements last mentioned include horizontally disposed arms extending in opposite directions and terminating in enlarged ends cut away to afford upper prongs 26 and 27, respectively, and lower prongs 28 and 29, respectively, and include downwardly projecting arms 30 and 31, respectively, constituting the other branch of the bell cranks. The last-mentioned arms 30, 31 are connected by a coil spring 32 tending to draw the same toward each other against stops 33 provided therefor on the sliding plate 5. The recessed enlarged ends of the bell crank elements embrace the studs 21 and 20 of the rocking lever 18 between the prongs 26, 28 and 27, 29 respectively, and the parts mentioned are of such relative dimensions that when one stud 21 is in the apex of the recess between prongs 26 and 28, the other stud 20 is at the wide opening between the other prongs 27 and 29, and vice versa. The lower prongs 28 and 29 are also provided on their rear faces with projecting studs 34 and 35 which extend through and beyond trapezoidal openings 36 and 37, respectively, in the main stamping 5. As will be apparent from the construction thus far described, movement of the plate 22 to the left in Fig. 1 carries the bell crank prong 29 against the stud 20 and raises the latter to rock rack 17 of lever 18 upwardly, and this motion is permitted by the coincident movement to the left of the opposite bell crank prong 28, which relatively brings the other lever stud 21 into the wide opening between prongs 26, 28, and thus causes the parts to assume the position shown in Fig. 3 where the oscillation of lever 18 is represented as effecting reversal of the ribbon guides 1 and 2.

The sliding plate 22 terminates in an upright 37 adapted for connection through a link 38 (Fig. 6) and arm 39 with the end of a forwardly extending shaft or rod 40 extending to the front of the machine for manipulation by the operator. Consequently, by rocking shaft 40 the position of the ribbon guides 1 and 2 may be expeditiously controlled at will to carry the e. g. black portion 41 of the ribbon above (Fig. 1), or below (Fig. 3) the e. g. red portion 42 thereof. In mounting, the device is positioned so that the upper color strip of the ribbon between the guides 1 and 2 registers with the instant printing line when the platen is in middle case or upper case position, and consequently, by reversing the face of the ribbon printing may be effected in either color desired by the mechanism described in the two case positions mentioned.

The parts of the ribbon guide mechanism thus far described are supported as shown in

Fig. 6, wherein stamping 5 is indicated as fitting a slot 43 between upturned portions of a bent bracket plate 44, the latter being rigidly fixed at 45 to a stationary cast block 46 of the machine base. Fig. 6 illustrates the mounting at only one end of the ribbon guide mechanism, but it is to be understood that a duplicate instruction and assembly is also provided for the other end thereof. Stamping 5 is normally pulled downwardly to seat against bracket 44 by a pair of coil springs 47, each being tensioned between an aperture in bracket 44 and an aperture in one of the stamping arms 4. The cast blocks 46 also constitute the pivotal supports of links 48 attached at their rear ends to the carriage rail 49 and adapted for suitable connection with the shift key levers for effecting vertical positioning of rail 49 in either one of three positions corresponding to the printing case positions of the platen.

Also rigidly fixed to the fore face of rail 49 is a stamped bracket 50 (Figs. 7, 8 and 9). This bracket comprises spaced forwardly extending arms 51 having right angled extremities for attachment by screws, or otherwise, with the carriage rail and a front horizontally disposed plate 52 having therein similar but oppositely disposed triangular openings 53, and having, also, on its fore face two spaced studs 54, 55. In assembly, the main stamping 5 is positioned with respect to bracket 50 so that the lugs 54 and 55 of the latter fit into vertical spaced slots 56 and 57 of the stamping 5. At the same time the studs 35 and 34 on the bell crank extremities 29 and 28, respectively, project through the triangular apertures 53 in bracket 50. These parts are so proportioned that stud 34 fits in the narrow apex 58 of one of the openings 53 while the other stud 35 is disposed in the vertically wide portion of the other opening 53 and vice versa.

As described, the bracket 50 is attached to and shifts vertically with the carriage rail 49 and platen thereon. With the ribbon guide mechanism in the position shown in Fig. 1, printing is effected through the upper color strip 41 of the ribbon in middle case position. Thereupon when the carriage is moved to upper case position stamping 5 and all the parts carried thereby are correspondingly elevated by the bracket 50, which seizes the stud 34 in the apex 58 of the corresponding bracket opening 53. Such elevation of the stamping 5 is permitted by its sliding movement in the slots 48 of bracket 44 against the action of coil springs 47, but this movement entails no reversal of the ribbon guides 1, 2, and accordingly the ribbon is merely elevated to maintain the strip 41 thereof in registry with the printing line for upper case position. When, however, the

carriage rail 49 is depressed to bring the platen through middle case position to lower case position, stamping 5 seats against brackets 44 and continued downward movement 5 of bracket 50 with the carriage rail causes a depression of stud 34 and with the latter stud 21 rock lever 18 and reverse the ribbon guides 1 and 2 thereby bringing the ribbon color strip 41 to lower position and in registration with the then printing line. The operation is similar with the parts positioned as in Fig. 3. That is to say, if the ribbon is turned to effect printing through the color strip 42 in middle and upper case positions, 10 then shifting of the carriage rail 49 to lower position causes stud 35 to be lowered by the wall of the other bracket opening 53 and thus stud 20 is lowered to rock the lever 18 in the other direction and reverse the guides 1 and 2, whereby the color strip 42 is kept in registration with the then printing line.

The embodiment of the invention above described is particularly designed for application to the Noiseless typewriter and is of 25 special advantage therewith, since the Noiseless machine includes a rigid bed plate positioned immediately in advance of the printing point and serving to support and guide the type carriers in their operation toward 30 and from the platen. Further, the typewriter ribbon is drawn above the surface of the bed plate mentioned and so closely adjacent thereto as to make objectionable its bodily lowering when the carriage is shifted 35 to lowest case position. By the mechanism as herein shown and described, however, a mere rotation of the intermediate ribbon portion 11 insures accurate and automatic registry of the selected color portion in the 40 different printing case positions, and this is accomplished by a minimum bodily displacement of the ribbon.

In order to yieldingly hold the ribbon tight, and also afford a clear length thereof 45 sufficient to take up twists in the plane thereof when rotated, the ribbon is threaded from spools 6 and 10 around pins 7 and 9, as indicated in Fig. 5. The construction of these pins is shown more clearly in Fig. 10, and 50 each comprises a spindle 59 which screws vertically into the machine frame adjacent the corresponding spool and carries a bent stamping 60 pivotally supported and urged by a coil spring 61 to carry an upright arm 55 62 and adjacent pin 63 toward the side of the machine. The ribbon is brought on the outer side of pin 59 and thence between end 62 and pin 63 so that the intermediate portion 11 of the ribbon may yield upon pressure 60 of the type carriers thereagainst and so that, further, rotation of the guides 1 and 2 is easily effected.

As many changes could be made in the above construction and many apparently 65 widely different embodiments of this invention

could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent is:

1. In a typewriting machine, in combination, a part shiftable to different printing case positions, a ribbon guide positioned in horizontal registry with the printing point, and means to effect a reversal of said ribbon guide upon movement of said shiftable part from one case position to another.

2. In combination, a part shiftable to different printing case positions, a ribbon guide to hold a ribbon in registry with the printing point, means to move said guide with said part when shifted to one position, and means to hold said guide against movement with said part when shifted to another position but to rotate said guide to maintain the same portion of the ribbon in registry with the printing point.

3. In combination, a shiftable part having three case positions, guides for a multi-color ribbon, means to rotate said guides at will to maintain either color portion of the ribbon in registry with the printing line in one case position of said part, and means to automatically maintain the same portion of the ribbon in registry with the printing line but faced oppositely thereto upon shifting of said part to another case position.

4. In a typewriting machine, in combination, a ribbon guide including spaced members to hold a ribbon in a plane substantially parallel to the printing plane, spaced horizontal bearings for said members, and means including a reciprocable plate to effect rotation of said members in said bearings through 180 degrees.

5. In combination, a supporting bracket having a horizontal body portion and upstanding spaced arms, ribbon guides pivotally supported on horizontal axes by said arms, a rock shaft journaled through said arms and operatively connected with said guides, a pinion on said shaft, a lever pivoted on said bracket and having a rack in mesh with said pinion, and means to move said lever to rock said shaft and rotate said guides through substantially 180 degrees at will.

6. In a typewriting machine, in combination, a part shiftable to different printing

case positions, a ribbon guide movable with said part in one direction, but held against movement with said part in the other direction, and means to rotate said guide upon movement of said part in said other direction.

7. In a typewriting machine, in combination, spaced ribbon spools, a guide intermediate said spools and adjacent the printing point, a ribbon threaded from said

spools to said guide, yieldable means to tension the ribbon adjacent said spools, and means to rotate said guide to reverse the ribbon adjacent the printing point.

In testimony whereof I affix my signature, 15
in the presence of two witnesses.

GEORGE GOULD GOING.
